CLAIM

The ornamental design for a utensil organizer, as shown and described.

DESCRIPTION

FIG. 1 is a perspective view of a utensil organizer, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is an another perspective view showing the utensil organizer, in another state.

All the broken lines in the drawings depict portions of the utensil organizer, that form no part of the claimed design.

1 Claim, 6 Drawing Sheets
